UNITED STATES PATENT OFFICE.

WILLIAM P. DAY, OF CLEVELAND, OHIO.

RAIL-INSULATING METALLIC TIE.

Application filed December 9, 1924. Serial No. 754,827.

To all whom it may concern:

Be it known that I, WILLIAM P. DAY, a citizen of the United States, residing at Cleveland, in the county of Cuyahoga and

5 State of Ohio, have invented certain new and useful Improvements in Rail-Insulating Metallic Ties, of which the following is a specification.

This invention relates to metallic ties for 10 railroads, and particularly to the metallic ties which are illustrated in my patents No. 1,317,779, granted on the 7th day of October, 1919, and No. 1,420,974, granted on the 22nd day of June, 1922.

15 In these patents and in other road beds known to me where metallic ties are used, all of the insulation has been placed under the rails and around the fastenings. This causes wear of the insulation because of the 20 fact that the insulation is placed beneath the rails and renders it difficult to place the insulation and to keep the insulation from wearing out.

The object of the present invention is to 25 provide a steel tie construction of the same general character as that disclosed in my prior patents above referred to but wherein the insulation is disposed at the middle of the tie. In other words, the tie is made in 30 two sections and the two sections of the tie are insulated from each other, thus placing the insulation at a point where it will not wear and where it is readily applied.

A further object is to provide a structure 35 of this character which is thoroughly strong and which is thoroughly fitted for steam railway construction particularly, though not limited thereto.

40 Other objects will appear in the course of the following description.

My invention is illustrated in the accompanying drawings, wherein:—

Figure 1 is a top plan view of a metallic rail tie constructed in accordance with my 45 invention;

Figure 2 is an elevation of the tie;

Figure 3 is a section on the line 3—3 of Figure 1;

Figure 4 is a sectional view on a horizontal plane through the joining ends of the bars 11 and 11^a, the filler block being 50 in section;

Figure 5 is a section on the line 5—5 of Figure 4;

Figure 6 is a top plan view of a modified 55 form of tie;

Figure 7 is an edge elevation of the tie shown in Figure 6;

Figure 8 is a section on the line 8—8 of Figure 6;

Figure 9 is a section on a horizontal plane through the meeting ends of the members 11^b and 11^c;

Figure 10 is a section on the line 10—10 of Figure 9;

Referring to Figures 1 to 5, in these drawings I have illustrated a steel tie constructed in general as are the steel ties disclosed in my prior patents. Each tie comprises the supporting plates 10 which 70 extend parallel to the rails and beneath the rails. These supporting plates are made of sheet steel three-eighths of an inch thick, the ends of the plate being so formed as to rest upon the transverse channel irons 11 and 11^a. The side walls of the plate extend downward and outward, as at 12, and the plate is formed with openings 13 for the attachment of rail fasteners 14. The plates are riveted or otherwise connected to the 80 transversely extending channel irons 11 and 11^a and, as heretofore stated in my prior patents, the channel irons 11 and 11^a together extend entirely across the road bed and both plates 10 were attached to a pair 85 of integral channel irons.

In the construction illustrated in Figure 1, the tie is made in two sections A and B, these sections being alike except that the plate 10 of the section B is disposed ahead 90 of the plate 10 of the section A. Riveted to the ends of the plate 10 of section A are the channel irons 11, and riveted to the ends of the plate 10 of the section B are the channel 95 irons 11^a. These channel irons 11^a are offset with relation to the channel irons 11, the channel irons 11 having their channels facing in one direction and the channel irons 11^a having their channels facing in the opposite direction, so that when the extremities of the channel irons 11^a are disposed in proper relation to the channel irons 11, the channels of the channel irons 11 and 11^a will face each other and the ends of 100 these channel irons will extend slightly past each other to a greater or less extent.

Disposed between the facing channel irons at the overlapping ends thereof are the insulating blocks 15 which may be made of hard wood, though any other suitable insulating material may be used. These insulating blocks are long enough to overlap both of 110

the channel irons and fit within the channels thereof and the blocks are held to the channels by means of bolts 16, thus securing a firm splice between the overlapping ends of the channel irons and at the same time thoroughly insulating them from each other. It will be noted that by placing the blocks 15 within the channels of the connecting bars 11 and 11^a that the two sections of the tie are held against independent movement in a vertical plane as well as independent movement in a horizontal plane and that the two rails are thoroughly insulated from each other and that this insulation is disposed at the middle of the road bed.

In road beds constructed in accordance with my invention, the middle portion thereof is covered with concrete or ballast so that this insulation is thoroughly protected from wear or damage. It is obvious that the block may be impregnated with a water-proofing compound and also coated with a water-proofing compound so that it will last indefinitely, or that other insulating materials having sufficient strength might be used in place of wood.

In Figure 6 I illustrate another form of my invention, in which the transverse channel bars do not extend straight across the road bed in all places at right angles to the rails, but in which a single channel iron 11^b is formed into an approximate triangle with its ends attached to the extremities of the plate 10. At the apex of the triangle, however, each channel iron is bent to form a portion 11^c which extends parallel to the axis of the plate 10 and both channel irons are formed with their channels facing outward so that the channels confront each other at this portion 11^c.

Disposed within these confronting faces of the channel irons is the insulating block 17, which is preferably made of hard wood, this insulating block being held by bolts 18 passing through the block and through the channel irons and bearing against filling blocks 19 which are disposed within the re-entrant portions of the apex of the triangle, the extremities of these filling blocks being beveled so as to fit against the web of the channel irons. By turning up on the nuts of the bolts 18, these filler blocks are forced into place, the two channel irons are forced into place against the wood block, and the two sections of the tie are held firmly engaged with each other against any deformation. Here, again, the two sections of the tie are insulated from each other so that the rails are insulated from each other and this insulation occurs at the middle of the tie where the insulation will be thoroughly protected, as heretofore explained.

The construction which I have described is particularly adapted for steam railroads

which carry a track circuit, and the purpose of the invention is to absolutely divorce one rail from the other. This construction is particularly desirable where steam railroads cross highways, that is where steam railroads cross paved streets on grade, though obviously I do not wish to be limited to this use of the invention.

While I have illustrated a tie of a particular form, that is the form covered by my prior patents, I do not wish to be limited to the exact details of construction as these might be changed without departing from the spirit of the invention as defined in the appended claims.

I claim:

1. A metallic tie formed in two sections, each section including channel irons, the channel irons of one section extending toward the channel irons of the other section and the channel iron of one section having its channel facing the corresponding channel iron of the other section, an insulating block disposed within the channels of both sections, and fastening devices disposed through the insulating blocks and the two sections and holding them in rigid engagement with each other.

2. A metallic tie formed in two lateral sections, each section including channel iron members extending toward each other, the channel iron members having their channels facing each other for a distance, an insulating block disposed in the channels of the two channel irons, and a bolt passing through the channel irons and through the insulating block and rigidly engaging the two sections with each other.

3. A metallic tie comprising a pair of parallel rail supporting plates, channel irons extending from the ends of each of said plates toward the other plate, the channel irons of one plate confronting the channel irons of the other plate for a distance and both of said channel irons having their channels facing toward each other, a block of insulating material disposed within said channel irons but spacing them from each other, and bolts passing through the channel irons and through said block.

4. A metallic tie of the character described comprising a pair of parallel metallic rail supporting plates, channel iron members attached to the ends of each of said plates and extending toward the other plate, the channel irons of one plate overlapping the channel irons of the other plate and the channels facing toward each other, and insulating blocks disposed within the channels of adjacent channel irons and spacing the adjacent channel irons from each other and being bolted thereto.

5. A metallic tie formed in two sections, each section including rail-supporting elements, metallic members attached to each

element and extending toward the other element, the members facing each other for a distance, an intermediate insulating block disposed between the confronting faces of the members and spacing the members from each other, and bolts passing through the members and blocks and holding them in engagement with the block, the block being thereby removable from between the members without shifting the members or the elements to which they are connected.

In testimony whereof I affix my signature.

WILLIAM P. DAY.
